FOUNTAIN STENCIL BRUSH

Milton B. Wright, St. Petersburg, Fla., assignor to
Universal Fountain Brush Company, Inc., a cor-
poration of Florida

Application December 2, 1936, Serial No. 113,903

3 Claims. (Cl. 15—138)

The present invention relates to fountain brushes and more particularly to stencil brushes used for marking packing cases and the like with a stencil.

The primary object of the invention is to provide in fountain brushes an improved structure whereby the bristles of the brush that are normally set in solid vulcanized rubber are prevented from turning and at the same time permitting an uninterrupted flow of liquid such as ink or paint into the bristles.

A further object is to provide a valve stem, connecting the liquid containing handle with the bristles of the brush, which provides for a better seat for the valve, thus eliminating the necessity of cleaning the valve at frequent intervals.

The invention will be fully and comprehensively understood from a consideration of the following detailed description when read in connection with the accompanying drawing which forms part of the application.

In the drawing:

Fig. 1 is an elevational view of the brush.

Fig. 2 is an enlarged sectional view taken on line 2—2 of Fig. 1; and

Fig. 3 is an exploded perspective view of the several parts connecting the liquid containing handle with the brush head.

The present invention may be considered as an improvement of Patent No. 1,348,681, granted August 3, 1920, and includes a number of elements disclosed in this patent. Generally stated, the device consists of a reservoir handle attached to a brush structure, the bristles of the brush surrounding a substantially square-shaped wedge that is tapered in one end and flared in an outward direction to prevent said bristles from covering the central outlet from the handle. A reservoir handle is connected to the brush head by means of a threaded valve stem, which stem is attached to the handle thru an intermediate threaded coupling member.

Referring to the drawing for a more detailed description thereof, the device includes a hollow reservoir handle 5 adapted to contain a liquid such as ink or paint. The open end of the handle is interiorly threaded at 6 for attachment to the cap 7. The end of the cap projecting within the handle is recessed and in the recessed portion there are provided a plurality of outlets 8 thru which the paint or ink contained within the handle 5 is fed to the brush. The lower end of the cap 7 is reduced in thickness and is formed with interior and exterior threads 10 and 9, respectively, for a purpose to be hereinafter described.

The brush head indicated generally by the numeral 11 includes an annular metallic ring 12 and cap 13, the cap 13 being formed of brass or other similar material. The bristles 14 of the brush are preferably set in vulcanized rubber and surround a square-shaped centrally disposed wedge 15, the end 16 of which is tapered and flared to prevent the bristles of the brush from covering the central outlet extending from the reservoir handle. The wedge 15 is preferably square shaped so as to prevent its turning when set in solid vulcanized rubber. The upper end of the wedge 15 is provided with a shoulder portion 17 on which the circular plate 18 is placed to form a backing for the ends of the bristles. The plate 18 is held in position by means of the annular ring 12, which ring is clamped into position by any suitable means.

The interior of the wedge 15 is threaded for receiving the threaded end 19 of a valve stem 20 which connects the handle 5 with the brush head 11. The liquid, such as paint or ink, flows from the handle 5 thru the openings 8 into the passage 21, thence into the bristles of the brush. It is of course to be understood that a central outlet extends thruout the length of the wedge 15. It will be noted that the stem 20 is exteriorly threaded thruout its length and that the upper end thereof is attached to the cap 7 and by means thereof the handle 5 is in direct communication with the brush head 11.

The upper end of the stem 20 is formed with a concave seat 22 for receiving the convexed end 23 of the cap 7, the members 22 and 23 constituting a closure valve between the reservoir handle 5 and the brush. The convexed end 23 is formed within a circular area corresponding to the series of outlets 8 which are also preferably arranged in a circular manner. The convexed end 23 when seated within the seat 22 closes the outlet from the handle to the brush head 11. A slight turn of the handle withdraws the convexed end 23 from its seat, thereby permitting the liquid to flow thru the outlets 8 into the passage 21.

For preventing leakage around the tapered end of the cap 7, there is provided a packing nut 24 and washer 25. The packing nut is threaded for engagement with the exterior threads 9 of the cap 7 and when in position thereon prevents any leakage of the liquid around the stem 20, the washer 25 being compressed to closely contact the threads of the stem 20. At that point on the stem 20 where the thread 19 begins, as indicated at 26, the stem 20 is preferably straight knurled so as to securely grip within a central opening 55

27 of the cap 13 into which same is pressed. When in position the stem and cap present a substantially unitary construction while permitting the use of different types of materials for 5 each part. It has heretofore been the practice of forming the stem 20 and cap 13 of a single piece of material and threading and shaping the same to the desired size, which process resulted in an appreciable waste of material. It will be 10 noted that the cap 13 is also provided with a groove 28 to accommodate the upper end of the annular ring 12, and that a washer 29 is interposed between the cap 13 and the plate 18.

It will be apparent that the brush comprising 15 the bristles 14 secured in a vulcanized setting surrounded by the annular ring 12 and having the wedge 15 firmly embedded within the bristles 14 by the vulcanized material, and including the plate 18 at its upper end forms a unitary construction 20 presenting a brush element adapted for convenient attachment to the cap 13. The wedge 15 being interiorly threaded is readily engaged on the device by screwing on to the threaded portion 19, the latter projecting from within the 25 cap 13 in which the washer 29 has been inserted.

A convolute spring 30 encircles the stem 20 and is interposed between the packing nut 24 and top face of the cap 13. The spring 30 has a normal tendency to exert pressure to compensate 30 for any inequalities in the threads of the stem 20 which further aids in preventing leakage of the liquid around these threads.

It is believed that the use of the brush and the advantages thereof are readily apparent to those 35 skilled in the art. The handle 5 contains a suitable quantity of a liquid such as paint or ink and when desiring to feed the liquid to the brush head the handle is rotated approximately one quarter of a turn relative to the brush head 11 or 40 a sufficient distance to separate the convexed end 23 from the concave seat 22 permitting the liquid to flow into the passage 21 thru the openings 8. When a sufficient quantity of liquid has been absorbed by the bristles 14, the handle 5 is rotated 45 in a reverse direction, thereby seating the end 23 on the seat 22 shutting off further flow of the liquid. The feature of the convexed and concave ends 22 and 23, respectively, provides for a more regulated flow of the liquid and also 50 eliminates the necessity of cleaning the device at frequent intervals. In devices of the kind using a flat type of seat, the residue of ink accumulates around the seat thereby slowing or stopping entirely the flow of liquid from the reservoir. 55 It is to be understood that this improvement is capable of extended application and is not confined to the exact showing of the drawing nor to the precise construction described and, therefore,

such changes and modifications may be made therein as do not affect the spirit of the invention nor exceed the scope thereof as expressed in the appended claims.

What is claimed as new is:

1. A fountain brush comprising in combination, 5 a reservoir handle, an interiorly threaded cap forming a closure for said handle, a brush head comprising a cap adapted to receive a brush element therein, a hollow stem mounted on said brush cap and extending into said handle cap and threadedly engaging the interior threads thereof and including a threaded shank extending from within said brush cap, and a brush element comprising a wedge block securely embedded therein and having a bore therethrough with interior threads for engagement with said threaded shank, said wedge block being polygonal in cross-section to prevent turning of same within said brush element. 10

15 2. A fountain brush comprising in combination, a reservoir handle, a cap forming a removable closure for said handle and including means for dispensing the contents thereof, a hollow stem extending from said cap, a brush head attached 20 to said stem and including an annular ring member, a second cap surrounding said annular ring, a wedge block disposed substantially centrally of said ring and having a passageway communicating with said hollow stem, the upper end 30 of said block being substantially square-shaped in cross section and the other end outwardly flared, and a shoulder portion formed in the square-shaped end of the block and receiving a circular plate, said plate forming a backing strip 35 for bristles mounted within said ring and surrounding said wedge block.

25 3. A fountain brush comprising in combination, a reservoir handle, a cap forming a removable closure for said handle and including means 40 for dispensing the contents thereof, a hollow stem extending from said cap, a brush head attached to said stem and including an annular ring member, a second cap surrounding said annular ring member, a wedge block disposed 45 substantially centrally of said ring and having a passageway communicating with said hollow stem, the upper end of said block being substantially square-shaped in cross section and the other end outwardly flared, a shoulder portion 50 forming a part of the square-shaped end of the block, a circular plate positioned on said shoulder portion and held thereon by said annular ring, said plate forming a backing strip for bristles mounted within said ring and surrounding said 55 wedge block.

MILTON B. WRIGHT.
